UNITED STATES PATENT OFFICE

WILLIAM KERNOCHAN, OF EAST ORANGE, NEW JERSEY

CARPET HOLDING DEVICE

Application filed December 4, 1930. Serial No. 500,103.

My invention relates to a new and improved carpet holding device.

One of the objects of my invention is to provide a new and improved stair-rod which can be applied to any staircase by unskilled labor and which can hold fine carpets or delicate rugs in position without any injury.

Another object of my invention is to provide a device for holding carpets on stairs which will permit a carpet or rug to be easily laid or removed without any injury thereto.

Another object of my invention is to provide a device of simple construction which shall be very cheap to manufacture.

15 Other objects of my invention will be set forth in the following description and drawings which illustrate a preferred embodiment thereof, it being understood that the above general statement of the objects of my invention is intended merely to generally explain the same and not to limit it in any manner.

Fig. 1 is a front elevation.

Fig. 2 is a top plan view.

Fig. 3 is an end view.

25 Fig. 4 is a perspective view showing the device in position.

The device is preferably made of a single piece of metal 1, which is bent and stamped into the shape shown in Figs. 2 and 3. The 30 piece of metal 1 can consist of an ordinary piece of sheet metal and it is formed with a bottom portion or base 1a, and an upstanding wall 1b which is preferably substantially perpendicular to said base portion 1a. The upstanding wall portion 1b is provided with forwardly inclined teeth 2, having the arcuate form shown in Fig. 2. The base 1a is provided with upstanding triangular teeth 3 which are stamped out of the base 1a, leaving openings 3a.

There are two rows of the teeth 3, as shown in Figs. 3 and 4.

These devices are applied to the angles of a 45 flight of stairs S, being held in position by means of screws 4. In this position the base teeth 3 are vertical, and the upper teeth 2 are forwardly inclined.

The carpet or rug C is laid in the manner 50 shown in Fig. 4, so that it is held in position

by the upstanding teeth 3 and by the forwardly inclined teeth 2.

In order to remove the carpet, it is merely necessary to bend it forwardly, in order to disengage it from the forwardly inclined teeth 2, and to then raise the carpet, in order to disengage it from the upstanding teeth 3.

It is therefore very simple to attach or to remove the carpet, and this can be done without any injury thereto.

In laying the carpet, it is desirable to start from the bottom step with the pile even, pushing the carpet between the teeth of the first stair rod and continuing in this manner up to the top step. In order to remove the carpet, the operator should start from the top step and pull gently upon the successive portions of the carpet, in order to release it from the successive stair-rods.

An important feature of my invention is 70 that the teeth 3 are perpendicular to the tread of the stairs, instead of being rearwardly inclined. This perpendicular position makes it possible to remove the rug or carpet from said teeth 3, without any injury thereto.

Another important feature of the invention is to have the teeth 3 of triangular shape, and to have said teeth substantially parallel to the risers of the flight of stairs. This also makes it possible to apply and to release the rug or carpet with a minimum of injury thereto. Likewise, the downwardly and forwardly inclined teeth 2 hold the carpet or rug securely in position, without injuring the same when the rug or carpet is removed.

85 In order to define the invention, the teeth 3 may be described as being upstanding, it being understood that this refers to teeth which are substantially perpendicular to the adjacent tread of the stairs as distinguished from teeth which are rearwardly inclined towards the adjacent riser of the stairs.

I have shown a preferred embodiment of my invention, but it is clear that numerous changes and omissions can be made without departing from its spirit.

90 This application is in part a continuation of my previously filed application No. 365,804.

I claim:

95 A carpet holding device of angular con- 100

figuration adapted to fit into an angle of a flight of stairs so that one part of said carpet holding device abuts the tread and the other part of said carpet holding device abuts the riser, the tread portion of said carpet holding device having substantially upstanding teeth having flat faces, the riser portion of said carpet holding device having downwardly and forwardly inclined teeth, the faces of the teeth of the said tread portion being substantially parallel to said riser portion.

In testimony whereof I affix my signature.

WILLIAM KERNOCHAN.
